US0D1111648S

(12) **United States Design Patent** (10) Patent No.: **US D1,111,648 S**
(45) Date of Patent: ** Feb. 10, 2026

(54) **ELECTRIC GRINDER**

(71) Applicant: **NINGBO CHEFSHERE KITCHEN TECHNOLOGY CO., LTD.**, Ningbo (CN)

(72) Inventor: **Guoping Zhang**, Ningbo (CN)

(**) Term: **15 Years**

(21) Appl. No.: **35/522,805**

(22) Filed: **Aug. 1, 2024**

(80) **Hague Agreement Data**

Int. Filing Date: **Aug. 1, 2024**

Int. Reg. No.: **DM/241370**

Int. Reg. Date: **Aug. 1, 2024**

Int. Reg. Pub. Date: **Nov. 1, 2024**

(30) **Foreign Application Priority Data**

Feb. 1, 2024 (CN) 202430070331.7

(51) **LOC (15) Cl.** 31-00

(52) **U.S. Cl.**

USPC **D7/372**

Assistant Examiner — Christine Marie Achen Zimmerman

(57) **CLAIM**

The ornamental design for an electric grinder as shown and described.

DESCRIPTION

1. Electric grinder

1.1 : Perspective

1.2 : Perspective

1.3 : Front

1.4: Back

1.5 : Left

1.6 : Right

1.7: Top

1.8: Bottom

The electric grinder is used for crushing items.

(Continued)

The broken lines in the drawings represent portions of the electric grinder that form no part of the claimed design.

1 Claim, 8 Drawing Sheets
